UNITED STATES PATENT OFFICE.

WALTER SCOTT, OF PLAINFIELD, NEW JERSEY.

CUSHIONING APPARATUS FOR PRINTING-PRESSES.

SPECIFICATION forming part of Letters Patent No. 288,872, dated November 20, 1883.

Application filed February 23, 1883. (No model.)

To all whom it may concern:

Be it known that I, WALTER SCOTT, of Plainfield, in the county of Union and State of New Jersey, have invented an Improvement in Cushioning Apparatus for Printing-Presses, of which the following is a specification.

Printing-presses have been made with a cylinder beneath the reciprocating bed, and stationary pistons or plungers, over which the cylinder passes near the ends of the stroke, so as to check the momentum of the bed and types, and cause the press to run more uniformly. With these cushioning-cylinders there is usually more or less vacuum action as the cylinder draws off the piston, and a disagreeable noise is produced as the air rushes into the cylinder. Valves have been used to admit air into the cylinder as the same draws off the piston, and they usually close and confine the air whenever the pressure increases in the cylinder and act independent of the weight to be arrested.

The object of my invention is, first, to open the valve at a time when the pressure within the cylinder is about the same as that of the atmosphere, and thereby prevent the vacuum action tending to retard the momentum of the bed, as heretofore usual; second, to close the valve automatically at the proper time, so that more or less air will be confined in proportion to the weight of form upon the bed, and the momentum of the bed will be stopped at the end of the stroke; third, to allow the piston packing to yield inwardly without injury in cases where a piece of paper or other substance may fall upon the piston or into the cylinder, so that injury may be prevented; and, fourth, to expand the packing of the piston as it may become worn, but only to expand it sufficiently to make it come into contact with the interior of the cylinder.

In the drawings, Figure 1 is a section of the cushioning-cylinder, and a representation of the other parts to which the invention relates. Fig. 2 is a face view; Fig. 3, a section in larger size of the yielding piston. Fig. 4 is a side view, and Fig. 5 an edge view of the cams that operate the valves.

The parts of the press are to be of any usual or desired character.

The frame is indicated by the dotted outline A, the impression-cylinder by the circle B. The bed C is above the cushioning-cylinders D. There may be two of these cylinders— 55 one near each end of the bed—or there may be but one such cylinder with a central partition, as shown.

The pistons or plungers E are represented as sustained by the hollow rods F and cross- 60 frames G, between the main frames A; but the cylinders may be transposed, so that the pistons are upon the bed and the cylinders stationary on the frame. In either instance there is an outlet-pipe from the cylinder or 65 from the piston through the piston-rod, and an air-chamber, a, and valve b, that when closed confines the air to form the cushion, or when open allows the air to pass in or out of the cylinder freely. 70

I do not limit myself as to any particular construction, as my improvement is available with almost all forms of cushioning apparatus.

The shaft H is rotated in harmony with the other parts of the press. It is represented as 75 deriving its motion from the shaft e of the impression-cylinder by the bevel-gears d e and shaft K, and upon this shaft H the cams hereinafter described might be placed; but it will usually be preferable to employ cross-shafts h 80 h, driven by the bevel-gears k k. Similar devices are at each end of the press, and the parts are timed to act properly with the bed at the opposite ends of its stroke. The cam L is made with a projection, 2, that acts upon 85 the spindle of the valve b, and raises the same as the cylinder D is drawing off the piston E, and the parts are placed so that the cam lifts the valve at about the time that the pressure within the cylinder is about the same as that 90 of the atmosphere; hence the air will pass freely into the cylinder as the same draws off the piston and prevent any vacuum action, and avoiding any noise, and at the same time removing any risk of vibration in the bed, 95 caused by the sudden rush of air into the cylinder. This cam should be secured to its shaft by a clamping-screw, in order to allow of the cam being adjusted to raise the valve at the required time. 100

The aforesaid device alone may be used; but I prefer also to employ a second cam, n, upon

the same shaft with an elevation, 3, that holds the valve *b* open the required length of time, and preventing it closing too soon, and as this cam passes from below the valve-stem such 5 valve closes and confines the air. The object of this is to confine only the required amount of air, so that the accumulated pressure is enough to overcome the inertia of the bed. If the valve is allowed to close sooner in the 10 movement of the press, the cushioning action is increased so as to be sufficient to stop a heavy form, and the reverse for light forms. The cam *n* may be moved upon and clamped to the shaft *h*; but I have shown a screw and 15 nut, 10, at the curved slot in the cam *L*, by means of which the two cams may be clamped together after adjustment. The index on the cam and the pointer upon the nut indicate the relative position of the cams when adapted to 20 forms of different weights. Each piston is made with a stationary head, *r*, permanently attached to the piston-rod. The ring-follower *s* is held in place upon studs or columns *s'*, extending out from the head *r*. Between *r* and 25 *s* there is a flexible packing, *t*, connected at one edge with the expander *u*, and the other edge serves to form a tight joint with the interior of the cylinder *D* in retaining the air-cushion. The expander *u* is made in four or 30 more sections, and it is provided with conoidal flanges 12 at its inner edges. The sections do not set closely together, but they are guided by and between the studs *s'*, and they are free to be pressed inwardly against 35 the action of bow or helical springs 16, that are placed between the shaft and the inner portions of the said sections. These springs, if unrestricted in their action, would expand the packing too much to allow it to enter within 40 the cylinder. To prevent this I employ the internal conoidal retainer, *w*, which is in the form of an annular flange surrounding the inclined or conoidal flanges 12. This retainer is adjustable lengthwise of the piston-rod by 45 set-nuts *x*. By this construction the expanders are retained, so that the packing is not unduly distended. It may, however, be pressed inwardly by any foreign substance—such as a sheet or piece of paper falling upon the piston—50 and injury to the parts be prevented. By adjusting the retainer the expansive packing may be enlarged or contracted.

In many of the cushioning devices hereto-

fore used, the pistons are movable endwise of the piston-rods, so that they may act earlier or 55 later in the stroke to confine the air. By my improvement this adjustment of the pistons is dispensed with.

Any suitable valves or cocks may be used, and, if more convenient, air-pipes may be employed between the pistons and the valves, so 60 that the valves or cocks and the automatic actuating mechanism may be placed in any convenient position on the press.

I claim as my invention—

1. The combination, with the reciprocating bed and air-cylinders and the stationary pistons in a printing-press, of a valve to confine the air, and an automatic lifting device, substantially as described, to open the valve when 70 the pressure in the cylinder is reduced to about the same as that of the atmosphere, substantially as set forth.

2. The combination, with the cushioning cylinder and piston, of a valve to retain the 75 air in the cylinder and a cam to raise the valve and to drop it, so that such valve closes at the proper moment, substantially as set forth.

3. The combination, with the cushioning 80 cylinder and piston, of a valve and two adjustable cams to open the valve and to allow it to close at the proper time, substantially as set forth.

4. The combination, with the expansive 85 packing and the piston, of segmental expanders, a spring, and a retainer to adjust the extent to which the expanders operate, substantially as set forth.

5. The combination, with the bed, cylinder, 90 piston, and valve, of a cam to allow the valve to close, and an index for aiding in the adjustment of the cam so as to confine the air-cushion in proportion to the weight to be arrested, substantially as set forth.

6. The combination, with the bed *C* and impression-cylinder *B*, of the cylinders, their pistons *E*, valves *b*, the cams *L*, shafts *h H K*, and bevel-gearing connecting the shafts, substantially as set forth.

Signed by me this 19th day of February, A.D. 1883.

WALTER SCOTT.
